UNITED STATES PATENT OFFICE.

THOMAS J. MITCHELL, OF UNIONTOWN, PENNSYLVANIA.

COKE CONVEYING AND SCREENING MECHANISM.

1,082,757.

Specification of Letters Patent. Patented Dec. 30, 1913.

Application filed April 27, 1912. Serial No. 693,664.

To all whom it may concern:

Be it known that I, THOMAS J. MITCHELL, a citizen of the United States, residing at Uniontown, in the county of Fayette and State of Pennsylvania, have invented a new and useful Coke Conveying and Screening Mechanism, of which the following is a specification.

This invention relates to mechanisms for receiving coke as it is forced from an oven and delivering the same to a car.

The primary object of the invention is to provide a mechanism of this character which receives the coke as the same is forced from the oven and delivers the same to the car, and at the same time screens the coke, removing the braize and ash, without elevating the conveyer to accomplish the screening.

A further object of the invention is to provide a conveyer which will screen the coke without breakage.

A still further object of the invention is to provide a coke transferring mechanism which while effectually removing the braize and ash from the same will lay the coke in the car, the "drop" of the coke which is usual in screening conveyers being avoided.

A still further object of the invention is to provide means which will receive the coke together with the braize and ash and convey the same to the point where the coke is delivered and then convey the braize and ash to a point beneath the wheeled support of the conveying mechanism.

A further object of the invention is to provide means for adjusting the delivery end of the conveyer with respect to the car which receives the coke.

In the drawings:—Figure 1 is a top plan view of the complete apparatus. Fig. 2 is a side elevation of the complete apparatus, the same being shown as receiving coke from an oven of the rectangular type and depositing the same within a car. Fig. 3 is a section on the line 2—2 of Fig. 2 looking in the direction of the arrow. Fig. 4 is a detail view of the conveyer. Fig. 5 is a perspective view of a portion of the conveyer belt, and Fig. 6 is an end elevation of a portion of said belt.

In the drawings, 10 designates the wheeled support for the conveying mechanism, said support being formed with the uprights 11 and 12 which are connected by the transverse beams 14. Supported by the upper ends of the beams 11 and 12 is a platform 15 sup-

porting a motor 16 which drives the gear 17 mounted on the lay shaft 18. This shaft through the pinion 19 which engages the beveled gear 20 drives the vertically disposed shaft 21, the gear 20 being mounted on the end portion of said shaft. The end portion of the shaft 21 adjacent said pinion is supported by the bracket 22 which is secured at the point 24 to the platform 15, said bracket also supporting the lay shaft 18. The end of the shaft 21 remote from the gear wheel is supported by brackets 25, a pinion 26 arranged on said shaft meshing with the beveled gear 27 which drives the axle 28, the wheeled support being propelled in this manner.

Disposed transversely of the wheeled support and arranged intermediate the two sets of vertical standards 11 and 12 is the conveyer 30. This conveyer is supported (reference being had to Fig. 3 of the drawings) by the vertically moving bearing block 31. This bearing block or beam is secured at either end to a tubular interiorly screw-threaded boxing 32. These boxings are disposed for vertical movement within the vertical housing 33, arranged parallel with the beams 11 and 12. Supported within the housing 33 and journaled to rotate therein are feed screws 34 which extend through the block 32. These feed screws extend beyond the upper end of the housings 33 and arranged on the reduced ends of said feed screws are beveled gears 35 which are driven by the shaft 36. Said shaft 36 is provided at either end with pinions 37, the shaft being driven by the gear 38 which meshes with the gear 39, driven by the motor 40.

It will be noted that as the feed screws 35 are rotated, vertical movement will be imparted to the bar 31 through the medium of the boxing 32, the support for the conveyer in this manner being raised and lowered. The conveyer is pivotally supported at its lower end, by trunnions carried by the beams 67, the same swinging on its pivot as the beam 31 is raised and lowered by the feed screws 34. Thus it will be noted that the conveyer may be adjusted with respect to the coke receiving car 43, the "drop" of the coke thus being accurately regulated as the car is gradually filled, the delivery end being lowered as the coke is placed in the bottom of the car, the same being gradually raised as the car is filled.

The conveyer belt, the construction of which will be hereinafter more fully described, is driven by sprockets mounted on the shaft 44. This shaft is provided with 5 the gear 45 which is driven by the shaft 46, a pinion 47 arranged on said shaft meshing with the gear 45. The shaft 46 participates in the movement of the conveyer and is supported for such movement by a bracket 48 10 which is secured to the conveyer. This shaft is driven by a gear 49 in mesh with a pinion disposed on its end remote from the pinion 47. The pinion 49 is driven by the gear 51 which, in turn, is driven by the 15 gear 52 of the motor which is so constructed that the movement of the conveyer on the pivot will not affect the driving mechanism for the conveyer.

The conveyer is composed of a series of 20 curved plates 54 which are carried by two endless chains 63. These chains pass along either side of the machine and around the sprockets at the receiving and delivery ends, the chains being driven by said sprockets. 25 These endless chains carry lugs 53 to which the curved slats are attached. The forward edge of each slat is curved upward and backward so as to form a series of pockets 56. The opposite or rear edge of each slat 30 is curved downward and backward so as to come beneath the front edge of the next succeeding slat, so arranged as to prevent any opening for material to fall inside the belt as the slats pass over the sprockets at the 35 ends. Where the slats 54 are wide, if it is found necessary, an additional slat 57 is riveted to the former in proper position so as to stiffen the slat and add additional capacity for carrying ashes and braize. The 40 curved end of one of the plates abuts an adjacent plate and secured to each plate and spaced at a point equidistant from its curved end and the curved end of the adjacent plate, is a second transversely disposed plate 57- 45 which as stated above, is for the purpose of stiffening the slats, the coke in transit resting upon the edges of the plate, the braize and ash falling within the pockets and between the plates. As before stated, the slats 54 are secured at either end to links of an 50 endless chain 63, forming a complete and continuous belt. The endless chain 63 has rollers 60 traveling in the guides formed by the beams 61, this construction providing 55 a support for the conveyer belt.

Extending from the wheeled support in the direction of the oven are beams 67, the end portions of which are supported by the obliquely disposed beams 68 which are secured to the uprights 11. A plurality of depending brackets 69 are secured to the beams 67 adjacent their ends. Pivoted supported by said brackets is a guard or deflector 70, these guards being adapted to register with 65 the side walls of the oven, the guards being

provided with notches 71 which receive the projecting ledge 72 which forms a continuation of the oven floor. These guards are raised and lowered by means of rods 73 which terminate in rack bars 76, the rack bars 76 being advanced or retarded by the gear 77 which is rotated by the gear 78, this movement being imparted to the gear 78 by means of the crank 79. It will be noted by this construction that as the rack bar 76 is advanced or retarded the guards 70 will be moved toward or from the oven.

In practice the coke is projected upon the conveyer as the same is forced from the oven, the oven as before stated, being of the rectangular type in which a plunger is inserted from one end and the charge forced from the other. The coke falls upon the conveyer in large pieces, and as before stated these pieces rest upon the edges of the plates 85 54 and 57, the "skin" being broken, and the braize and ash being deposited within the pockets formed by curving the plates. Thus the braize and coke are conveyed independently, the coke resting upon the plate and the braize being housed by the pockets formed by curving the plates. The coke is conveyed to the delivery end of the conveyer and deposited within the car, the braize and ash being retained by the curved plates 95 even as the same pass over the sprockets disposed adjacent the delivery end of the conveyer. The pockets then descend within a trough 79, the terminal 80 of which is curved upward to receive the braize and ash which 100 may fall from the pockets. The braize or ash is then conveyed through the trough 79, being conducted by the curved ends of the plates. This trough adjacent the delivery end 42 of the conveyer lies parallel with 105 said delivery end which is slightly offset from the body of the conveyer. At the point 82 the trough is inclined and descends to a point adjacent the center of the conveyer which is disposed at the center of the wheeled support, the braize or ash then being deposited through an opening in said support. It will be noted by this construction that the braize and ash is effectually removed from 110 the coke without unduly elevating the same 115 the only elevation necessary to the conveyer being the elevation of the delivery end, which elevation is necessary as the height of the coke in the receiving car increases, the delivery end of the conveyer being retained at a point with respect to the car so as to "lay" the coke in large chunks in the car avoiding breakage. Thus the coke is effectually screened and at the same time delivered to the car without breakage.

Particular attention is called to the peculiar construction of the conveyer belt, the same forming braize receiving pockets, the coke being supported above said pockets. The invention consists in providing means 120 125

for conveying and screening the coke without unnecessary elevation of the same such as is done where the coke is elevated and dropped over a screen to separate the ash and braize before passing to the railroad car for transportation which latter method is objectionable on account of both the additional elevation necessary and also the drop over a screen which causes breakage of the coke in falling over the screen onto the car. Attention is also called to the peculiar manner in which the conveyer is supported and means for vertically adjusting the delivery end of the same. It will also be noted that the peculiar formation of the conveyer belt and the angle at which the curved end portions of the plates 54 and 57 are disposed, form pockets for the braize or ash, these pockets being so disposed that as before stated the conveyer in rounding the sprocket at its delivery end, does not permit the braize or ash to fall. It will be seen that the pockets will scrape the material along the spout or chute 79, preventing the chute from becoming clogged.

What is claimed is:

1. A mechanism for conveying and screening coke including a conveying member which receives the coke and ash from the oven, said coke and ash being carried for the entire length of the conveyer and means for returning the ash to a point adjacent the receiving end of the conveyer.

2. Coke conveying and separating mechanism including an endless conveyer comprising flexibly connected members having outstanding portions the free edges of which constitute coke supporting and carrying means, said members forming ash receiving pockets below the supported coke and which are shaped to retain the ashes after conveying the coke to the point of delivery.

3. Coke conveying and separating mechanism including an endless conveyer comprising flexibly connected members having outstanding portions the free edges of which constitute coke supporting and carrying means, said members forming ash receiving pockets below the supported coke and which are shaped to retain the ashes after conveying the coke to the point of delivery, and means for receiving the ashes when delivered from the pockets.

4. Coke conveying and separating mechanism including an endless conveyer comprising flexibly connected members having outstanding pockets, those pockets of the active flight of the conveyer being substantially inverted, the free edges of the said inverted pockets constituting coke supporting and carrying members, the spaces between said inverted pockets adapted to receive ashes from the coke thereabove, said pockets being movable from inverted to active positions during the discharge of the

coke thereabove, thereby to retain the ashes discharged between the pockets.

5. Coke conveying and separating mechanism including an endless conveyer comprising flexibly connected members having outstanding pockets, those pockets of the active flight of the conveyer being substantially inverted, the free edges of the said inverted pockets constituting coke supporting and carrying members, the spaces between said inverted pockets adapted to receive ashes from the coke thereabove, said pockets being movable from inverted to active positions during the discharge of the coke thereabove, thereby to retain the ashes discharged between the pockets, and deflecting means for receiving the ashes from the pockets.

6. Apparatus for conveying and separating coke, comprising an endless conveyer made up of flexibly connected imperforate members forming inclined upper and lower flights, the uppermost portion of the lower flight being extended substantially horizontally, deflecting means disposed under said horizontally extended portion, each of the members of the conveyer having outstanding pockets, the pockets of the upper flight being substantially inverted and having their free edges adapted to support and carry coke, the spaces between these inverted pockets being adapted to receive ashes from the coke supported thereabove, said pockets being movable from inverted to active positions while passing from the upper to the lower flights, thereby to retain the ashes until brought to position above the deflecting means.

7. A combined coke conveyer and separator, including an endless conveyer made up of flexibly connected members forming upper and lower flights, the said members having pockets extending throughout the width thereof, the pockets of the members constituting the upper flight being substantially inverted and having their upper edges constituting means for supporting coke above and outside of the pockets, the spaces between said inverted pockets being adapted to receive ashes from the coke thereabove, said pockets being movable from inverted to active positions while passing from the upper to the lower flights, thereby to retain the ashes during the discharge of the coke from the uppermost portion of the conveyer.

8. A combined coke conveyer and separator including an endless conveyer made up of flexibly connected members forming upper and lower flights, the said members having pockets extending throughout the width thereof, the pockets of the members constituting the upper flight being substantially inverted and having their upper edges constituting means for supporting coke.

above and outside of the pockets, the spaces between said inverted pockets being adapted to receive ashes from the coke thereabove, said pockets being movable from inverted to active positions while passing from the upper to the lower flights, thereby to retain the ashes during the discharge of the coke from the uppermost portion of the conveyer, and a trough for receiving the ashes subse-

quent to the discharge of the coke from 10 above the pockets containing the same.

In testimony that I claim the foregoing as my own, I have hereto affixed my signature in the presence of two witnesses.

THOMAS J. MITCHELL.
